Inventor
J. P. Hale

UNITED STATES PATENT OFFICE.

JOHN P. HALE, OF KANAWHA COURT-HOUSE, VIRGINIA.

IMPROVEMENT IN EVAPORATING-VESSELS.

Specification forming part of Letters Patent No. 26,182, dated November 22, 1859.

To all whom it may concern:

Be it known that I, JOHN P. HALE, of Kanawha Court-House, in the county of Kanawha and State of Virginia, have invented certain new and useful Improvements in the Process of Evaporating Brine and other Liquids and Solutions; and I do hereby declare that the following is a full, clear, and exact description of the same, reference being had to the accompanying drawings, making part of this specification, in which—

Figure 1 is a plan of a brine-evaporating apparatus illustrating my invention. Fig. 2 is a vertical section of the apparatus in the plane indicated by the line *x x* in Figs. 1 and 3. Fig. 3 is a vertical section of the same in the plane indicated by the line *y y* in Figs. 1 and 2.

Similar letters of reference indicate corresponding parts in the several figures.

My invention consists in the employment of superheated steam as in superheating the steam generated from the liquid at one stage of the evaporating process, or in one part of the evaporating apparatus by passing it through suitable heaters, and employing it, when so superheated, to heat and evaporate the liquid which is at another stage of the process or in another part of the apparatus.

To enable others skilled in the art to make and use my invention, I will proceed to describe the apparatus by which it is performed and its operation.

A represents a boiler, such as is commonly used for what is termed "boiling," which constitutes the first stage of the evaporating process in the manufacture of salt, as commonly practiced in many places, said boiler being made, with the exception of its bottom, of wood.

B is the furnace for heating said boiler, arranged below it.

C is the chimney.

D D' are two evaporating-cisterns, arranged lower than the boiler, to receive the brine therefrom after it has been evaporated to a certain degree, one of said cisterns, *D*, being represented with a lining, *a a*, or false bottom, and sides of metal, and the other, *D'*, being

represented as containing a pipe, *b*, or coil to illustrate the two most convenient methods of employing the superheated steam to heat their contents.

E E' are the steam-pipes leading from the boiler to the cisterns *D D'*, the former communicating with the space between the exterior and hollow lining of the cistern *D*, and the latter to the pipe or coil *b* that is within the cistern *D'*. These pipes *E E'* pass through the furnace for the purpose of causing the steam to be superheated on its way from the boiler to the cisterns. The said pipes may, however, be heated by the waste heat in the chimney, instead of in the furnace itself; or they may connect with superheating-vessels of any desirable form in the furnace or chimney. With the exception of the arrangements for superheating the steam, the above-described apparatus does not materially differ from the apparatus that is in common use for evaporating brine, and is well known.

By the use of my improvement the evaporation will be much expedited. Each cistern or evaporating-vessel will be capable of performing a greater amount of work, and hence a smaller number will be required to do a given amount of work in a given time, and so the first cost of apparatus will be reduced, and the loss by leakage and wastage of various kinds from the cisterns or vessels that are dispensed with will be avoided.

My invention is also applicable to the drying of salt or other substances subsequently to the so-called evaporating process.

I do not claim the use of the vapor arising from one portion of the liquid to be evaporated for heating or evaporating another portion of the liquid.

What I claim as my invention, and desire to secure by Letters Patent, is—

The superheating of the steam or vapor arising from the evaporation of the brine, substantially as and for the purpose herein shown and described.

J. P. HALE.
